CLAIM

The ornamental design for a computer screen with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of an embodiment of a computer screen with graphical user interface.

The outermost broken lines depict a computer screen or portion thereof that forms no part of the claimed design. The remaining broken lines illustrate portions of the graphical user interface that form no part of the claimed design.
